CLAIM

The ornamental design for a confection, as shown and described.

DESCRIPTION

FIG. 1 is a front perspective view of a confection showing my new design according to a first embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is bottom plan view thereof;

FIG. 8 is a front perspective view of a confection showing my new design according to a second embodiment;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is bottom plan view thereof;

FIG. 15 is a cross-sectional view taken along the line 15-15 in FIG. 8;

FIG. 16 is a front perspective view of a confection showing my new design according to a third embodiment;

FIG. 17 is a front elevation view thereof;

FIG. 18 is a rear elevation view thereof;

FIG. 19 is a right side elevation view thereof;

FIG. 20 is a left side elevation view thereof;

FIG. 21 is a top plan view thereof;

FIG. 22 is bottom plan view thereof;

FIG. 23 is a front perspective view of a confection showing my new design according to a fourth embodiment;

FIG. 24 is a front elevation view thereof;

FIG. 25 is a rear elevation view thereof;

FIG. 26 is a right side elevation view thereof;

FIG. 27 is a left side elevation view thereof;

FIG. 28 is a top plan view thereof;

FIG. 29 is bottom plan view thereof; and,

FIG. 30 is a cross-sectional view taken along the line 30-30 in FIG. 23.

The larger stippled shading, smaller stippled shading, and non-stippled areas shown in the drawings illustrate a contrasting appearance.

The broken lines in the drawings illustrate portions of the confection that form no part of the claimed design.

1 Claim, 26 Drawing Sheets
